The ornamental design for a separator for fuel cell, as shown and described.

(51) **LOC (9) Cl.** **13-01**
(52) **U.S. Cl.** **D13/122; D13/118**
(58) **Field of Classification Search** D13/118,

DESCRIPTION

D13/101, 103, 199; D21/494; D25/102,
D25/113, 118, 138; 29/623, 623.1; 204/242,
204/254-257; 429/19, 30-39, 99, 100

FIG. 1 is a perspective view of top, front and right side of a separator for fuel cell showing our new design;

See application file for complete search history.

FIG. 2 is a left side view thereof, the right side view is identical thereof;

FIG. 3 is a front view thereof;

FIG. 4 is a rear view thereof;

FIG. 5 is a top plan view thereof, the bottom view is identical thereof; and,

FIG. 6 is a partially enlarged view thereof.
